UNITED STATES PATENT OFFICE.

HARRY C. UMPLBY AND MARTIN J. BUTLER, OF ANGELICA, NEW YORK.

HOSE-CLAMP.

No. 892,197.

Specification of Letters Patent.

Patented June 30, 1908.

Application filed August 12, 1907. Serial No. 388,278.

To all whom it may concern:

Be it known that we, HARRY C. UMPLBY and MARTIN J. BUTLER, citizens of the United States, residing at Angelica, in the county of Allegany and State of New York, have invented certain new and useful Improvements in Hose-Clamps, of which the following is a specification.

This invention relates to hose-clamps for attaching the hose to a nozzle, coupling, etc., and has for its object to provide a simple and efficient clamp which can be easily applied and removed without the use of a tool.

In the accompanying drawing, Figure 1 is an end view of the clamp showing the application thereof, the release position being shown in dotted lines. Fig. 2 is a plan view.

In the drawings, 5 denotes a section of hose which is to be clamped to a nozzle or coupling indicated at 6. The clamp comprises a flexible band of spring metal made in two sections indicated at 7 and 8 respectively, said sections having a hinge connection 9. The sections lap at their free ends 25 and on the section 7 is an abutment 10 which is engageable by a hook 11, connected to a lever 12 carried by the section 8.

On the section 8 are ears 13 to which the lever 12 is pivoted as indicated at 14. Adjacent its pivot, the lever has a lateral extension 15 to which the hook 11 is pivoted.

The hook is locked by passing its free end between ears 16 on the section 8 and inserting a pin 17 through alined openings therein above the key.

In use, when the hook 11 is disengaged from the abutment 10 the sections 7 and 8 can be opened and placed around the hose.

The lever 12 is then swung down between the ears which draws the two sections tightly together against the hose, and securely fastens it to the part 6, and upon inserting the pin 17 in the openings in the ears 16 the lever will be securely locked therebetween.

The clamp herein described is simple in construction and can be readily applied or removed, and it effectually serves the purpose for which it is intended.

The lever 12 is straight and extends tangentially to the section 8 of the band and also beyond the ears 16, in view of which it can be more easily taken hold of to apply or remove the coupling.

We claim:

A hose clamp comprising a flexible split band having at one of its ends an abutment, ears on the other end of the band, a lever adapted to extend tangentially to the band, and having lateral extensions at one end, a pivotal connection between one of said extensions and the ears, a hook pivoted to the other extension and engageable with the abutment, ears on the band beyond the point of tangency of the lever and having alined openings, between which ears the lever is adapted to be placed with its free end spaced from the band, and a pin passing through the openings in the ears for locking the lever therebetween.

In testimony whereof we affix our signatures, in presence of two witnesses.

HARRY C. UMPLBY.
MARTIN J. BUTLER.
